FIG. 3 is a top plan view thereof, the bottom plan view being a mirror image;

FIG. 4 is a left side elevational view thereof, the right side elevational view being a mirror image;

FIG. 5 is a perspective view of a gasket for an electric plug showing a second embodiment of our new design;

FIG. 6 is a front elevational view thereof, the rear elevational view being a mirror image;

FIG. 7 is a top plan view thereof, the bottom plan view being a mirror image;

FIG. 8 is a left side elevational view thereof, the right side elevational view being a mirror image;

FIG. 9 is a perspective view of a gasket for an electric plug showing a third embodiment of our new design;

FIG. 10 is a front elevational view thereof, the rear elevational view being a mirror image;

FIG. 11 is a top plan view thereof, the bottom plan view being a mirror image;

FIG. 12 is a left side elevational view thereof, the right side elevational view being a mirror image;

FIG. 13 is a perspective view of a gasket for an electric plug showing a fourth embodiment of our new design;

FIG. 14 is a front elevational view thereof, the rear elevational view being a mirror image;

FIG. 15 is a top plan view thereof, the bottom plan view being a mirror image;

FIG. 16 is a left side elevational view thereof, the right side elevational view being a mirror image;

FIG. 17 is a perspective view of a gasket for an electric plug showing a fifth embodiment of our new design;

FIG. 18 is a front elevational view thereof, the rear elevational view being a mirror image;

FIG. 19 is a top plan view thereof, the bottom plan view being a mirror image; and,

FIG. 20 is a left side elevational view thereof, the right side elevational view being a mirror image.

The broken lines shown represent unclaimed subject matter and form no part of the claimed design.
